FRANK STRICKLAND, OF MUSKOGEE, INDIAN TERRITORY.

TRANSMISSION MECHANISM.

No. 844,210.

Specification of Letters Patent.

Patented Feb. 12, 1907.

Application filed June 9, 1906. Serial No. 320,960.

To all whom it may concern:

Be it known that I, FRANK STRICKLAND, a citizen of the United States, and a resident of Muskogee, District 10, Indian Territory, 5 have invented a new and Improved Transmission Mechanism, of which the following is a full, clear, and exact description.

This invention relates to transmission mechanisms.

10 The object of the invention is to produce a mechanism of this class which will operate to transmit power at a varying-speed ratio.

The invention is applicable in connection with many machines having a reciprocating 15 part which does work on one stroke only. By means of the invention the return stroke is made at a greater speed, so that the power is most advantageously applied to the work.

The invention consists in the construction 20 and combination of parts to be more fully described hereinafter and particularly set forth in the claims.

Reference is to be had to the accompanying 25 drawings, forming a part of this specification, in which similar characters of reference indicate corresponding parts in both views.

Figure 1 is a side elevation of the mechanism, a portion of the frame thereof being broken away; and Fig. 2 is a plan of the 30 mechanism, certain parts being broken away and shown in section to disclose the structure more completely.

Referring more particularly to the parts, 1 represents the frame of the mechanism, 35 which may have the rectangular form shown in Fig. 2, said frame being supported upon legs 2, as indicated in Fig. 1. This frame 1 presents oppositely-disposed parallel side bars 3. On these side bars 3 there is rotatably mounted a pair of gear-wheels 4 and 5, 40 which are rigidly attached together. Meshing with these gears there is a second pair of gear-wheels 6 and 7. These gear-wheels 6 and 7 are not rigid with each other, the gear-wheel 6 being rigidly attached to a tubular shaft 8, which projects at one side of the frame and carries a rigid crank 9, as indicated. To this crank 9 a pitman or connecting-rod 10 is attached, and this pitman affords means 45 for transmitting power to the transmission mechanism by any suitable means, such as the cylinder 11. The gear-wheel 7 is rigidly attached to a shaft 12, which carries a rigid crank 13, and this crank 13 has attached 50 thereto a pitman or connecting-rod 14. The

lower extremity of this connecting-rod 14 is attached pivotally to a cross-head pin 15, which is carried by a plunger or piston 16, to which the power is being transmitted. This plunger 16 is guided in a vertical direction 60 through a suitable guide-bracket 17.

As indicated most clearly in Fig. 1, the gear-wheels 4 and 6 are of common form, being circular and mounted upon the geometrical centers of the axes of rotation. The gear-wheels 5 and 7, however, are of special form. That portion of the gear-wheel 5 which is disposed to the left of a vertical line passing through the shaft of this gear is substantially circular, but the right-hand portion of the gear is extended laterally on a horizontal axis, so that the gear-wheel presents substantially the outline of an egg or oval. The gear-wheel 7, which meshes with this gear, is correspondingly but oppositely 75 formed—that is, its half portion which lies to the right of a vertical line passing through the axis of the gear is of substantially circular form, while the half portion of the gear adjacent to the gear-wheel 5, as viewed in Fig. 1, 80 is flattened as indicated—that is, the degree of curvature of the pitch part of the gear is reduced. The gears mesh with each other as indicated, so that when one of the gears is presenting an abnormally long radius from 85 its axis to the pitch-lines of the gears at their point of tangency the opposite gear will present an abnormally short radius. The gears are laid out so that their pitch-lines will be constantly tangent while they roll upon each 90 other. In this way the speed ratio between the gears is constantly changing, and during part of the revolution one of the gears will rotate at a higher speed than the other, while during the rest of the rotation the other gear 95 will rotate at a higher speed. From this arrangement and from an inspection of Fig. 1 it will be evident that upon the upstroke of the plunger 16 the plunger will be moving at a lower velocity than upon its downstroke, 100 the direction of rotation being that represented by the arrow shown in Fig. 1. Evidently the speed of the plunger will be accelerating on the downstroke until the point is reached near the mid-position of the plunger, 105 whereupon the velocity will diminish gradually to the end of the stroke. The movement in the opposite direction will be substantially uniform, since the radii of the gears on this stroke will remain at a substantially 110

constant ratio. Such a movement as this is a highly advantageous one in many connections where the power is to be delivered principally on one stroke of the plunger. An ordinary hay-baling press is an example of a case in which the transmission mechanism can be very advantageously employed. The slow movement of the plunger will be utilized for compressing the bale of hay, while the return movement of the plunger will be quickly accomplished.

Having thus described my invention, I claim as new and desire to secure by Letters Patent—

- 15 1. In a transmission mechanism, in combination, a substantially rectangular frame, a gear-wheel of substantially circular form mounted in said frame, a second gear-wheel of substantially circular form mounted in said frame and meshing with said first gear-wheel, a third gear-wheel rigid with said second gear-wheel, a fourth gear-wheel having the same axis of rotation with said first gear-wheel and independently rotatable with respect to the same, said fourth gear-wheel meshing with said third gear-wheel, said third and fourth gear-wheels having an irregular form producing a variable-speed ratio between the same, a crank carried by said first gear-wheel, a connecting-rod attached to said crank and affording means for rotating the same at a substantially uniform speed, a crank rigid with said fourth gear-wheel, a plunger; means for guiding the same to slide longitudinally, a connecting-rod connecting said second 60 crank with said plunger whereby said plunger may be driven at a slow speed on its forward stroke and at a high speed on the return stroke, a tubular shaft carrying said first gear and said first crank, and a shaft carrying said 65 fourth gear-wheel and rotatably mounted in said tubular shaft and in said frame.
- 20 2. In a transmission mechanism, in combination, a substantially rectangular frame, a gear-wheel of substantially circular form mounted in said frame, a second gear-wheel of substantially circular form mounted in said frame and meshing with said first gear-wheel, a third gear-wheel rigid with said second gear-wheel, a fourth gear-wheel having the same axis of rotation with said first gear-wheel and independently rotatable with respect to the same, said fourth gear-wheel meshing with said third gear-wheel, said third and fourth gear-wheels having an irregular form producing a variable-speed ratio between the same, a crank carried by said 65 first gear-wheel, a connecting-rod attached to said crank and affording means for rotating the same at a substantially uniform speed, a crank rigid with said fourth gear-wheel, a plunger; means for guiding the same to slide longitudinally, a connecting-rod connecting said second 70 crank with said plunger whereby said plunger may be driven at a slow speed on its forward stroke and at a high speed on the return stroke, a tubular shaft carrying said first gear and said first crank, and a shaft carrying said fourth gear-wheel and rotatably mounted in said tubular shaft and in said frame.
- 25 3. In a transmission mechanism, in combination, a substantially rectangular frame, a gear-wheel of substantially circular form mounted in said frame, a second gear-wheel of substantially circular form mounted in said frame and meshing with said first gear-wheel, a third gear-wheel rigid with said second gear-wheel, a fourth gear-wheel having the same axis of rotation with said first gear-wheel and independently rotatable with respect to the same, said fourth gear-wheel meshing with said third gear-wheel, said third and fourth gear-wheels having an irregular form producing a variable-speed ratio between the same, a crank carried by said 75 first gear-wheel, a connecting-rod attached to said crank and affording means for rotating the same at a substantially uniform speed, a crank rigid with said fourth gear-wheel, a plunger; means for guiding the same to slide longitudinally, a connecting-rod connecting said second 80 crank with said plunger whereby said plunger may be driven at a slow speed on its forward stroke and at a high speed on the return stroke, a tubular shaft carrying said first gear and said first crank, and a shaft carrying said fourth gear-wheel and rotatably mounted in said tubular shaft and in said frame.
- 30 4. In a transmission mechanism, in combination, a substantially rectangular frame, a gear-wheel of substantially circular form mounted in said frame, a second gear-wheel of substantially circular form mounted in said frame and meshing with said first gear-wheel, a third gear-wheel rigid with said second gear-wheel, a fourth gear-wheel having the same axis of rotation with said first gear-wheel and independently rotatable with respect to the same, said fourth gear-wheel meshing with said third gear-wheel, said third and fourth gear-wheels having an irregular form producing a variable-speed ratio between the same, a crank carried by said 85 first gear-wheel, a connecting-rod attached to said crank and affording means for rotating the same at a substantially uniform speed, a crank rigid with said fourth gear-wheel, a plunger; means for guiding the same to slide longitudinally, a connecting-rod connecting said second 90 crank with said plunger whereby said plunger may be driven at a slow speed on its forward stroke and at a high speed on the return stroke, a tubular shaft carrying said first gear and said first crank, and a shaft carrying said fourth gear-wheel and rotatably mounted in said tubular shaft and in said frame.
- 35 5. In a transmission mechanism, in combination, a substantially rectangular frame, a gear-wheel of substantially circular form mounted in said frame, a second gear-wheel of substantially circular form mounted in said frame and meshing with said first gear-wheel, a third gear-wheel rigid with said second gear-wheel, a fourth gear-wheel having the same axis of rotation with said first gear-wheel and independently rotatable with respect to the same, said fourth gear-wheel meshing with said third gear-wheel, said third and fourth gear-wheels having an irregular form producing a variable-speed ratio between the same, a crank carried by said 95 first gear-wheel, a connecting-rod attached to said crank and affording means for rotating the same at a substantially uniform speed, a crank rigid with said fourth gear-wheel, a plunger; means for guiding the same to slide longitudinally, a connecting-rod connecting said second 100 crank with said plunger whereby said plunger may be driven at a slow speed on its forward stroke and at a high speed on the return stroke, a tubular shaft carrying said first gear and said first crank, and a shaft carrying said fourth gear-wheel and rotatably mounted in said tubular shaft and in said frame.

In testimony whereof I have signed my name to this specification in the presence of two subscribing witnesses.

FRANK STRICKLAND.
